UNITED STATES PATENT OFFICE.

JOSEPH D. HUBBARD, OF CHICAGO, ILLINOIS.

CABINET-FILE.

SPECIFICATION forming part of Letters Patent No. 415,782, dated November 26, 1889.

Application filed March 18, 1889. Serial No. 303,746. (No model.)

To all whom it may concern:

Be it known that I, JOSEPH D. HUBBARD, residing at Chicago, in the county of Cook and State of Illinois, and a citizen of the 5 United States, have invented a new and useful Improvement in Cabinet-Files, of which the following is a specification, reference being had to the accompanying drawings, in which—

10 Figure 1 is a perspective view showing the cover raised. Fig. 2 is a detail showing one of the pockets. Fig. 3 is a vertical longitudinal section.

This invention relates to cabinet-files, and 15 is primarily designed to contain legal blanks. Its object is to provide an improved cabinet containing a series of pockets in which legal blanks can be held, so as to be easily accessible, which I accomplish as illustrated in the 20 drawings, and hereinafter described.

That which I claim as new will be pointed out in the claim.

In the drawings, A represents the main 25 part of the case, the sides of which, as shown, are cut diagonally.

B is the cover. The sides of the cover B also are cut diagonally, and it is so hinged to the case A that when closed the cabinet will be rectangular in form. This cover B is 30 hinged to a piece a on the upper rear end of the case A.

C C are two upright rods located at the rear end of the cabinet beneath the piece a.

D represents one of a series of pockets 35 adapted to contain legal blanks or other papers. Each pocket D is made of Manila paper or other suitable material, and consists of a main portion provided with a flap d on each side, which extend about two-thirds of the 40 length of the main portion, as shown in Fig. 2. The flaps d may be made integral with the main portion and re-enforced at the fold by a piece of cloth; or they may be made separately and attached by a piece of cloth. Each 45 pocket D is provided with two holes c at its rear end for the rods C, which may be re-enforced to prevent tearing, as shown in Fig. 2.

E is the cover-supporter. This supporter consists of a long piece of metal, provided with a slot e at each end, and is secured to

the cover B and case A by pins or screws b, which pass through the slots e.

F is a metal rod, which may be bent into the form of a bail, as shown in Fig. 1. The ends of the rod F are pivoted to the inside of 55 the cover B at f, about midway of its length.

G are two springs coiled around the ends of the bent rod F. Each spring is so arranged that it operates to press the rod F 60 against the cover B.

An index-page may be provided for convenience, which can be placed on top of the series of pockets, as shown in Fig. 1.

In use the legal blanks or other papers to be filed are placed in the pockets, which are 65 numbered consecutively, and the number of the pocket and the name of the blank or paper placed on the index. When any one of the blanks or papers is desired, the cover B is to be raised, as shown in Figs. 1 and 3, and 70 the pockets above the one in which the desired paper is held are to be raised up and turned back, and at the same time the bent rod or bail F is also to be raised and the front ends of the raised pockets passed between the rod or bail F and the cover B. The 75 rod F, being then released, holds the pockets in the raised position until it is again lifted, when the pockets can be returned to their normal position.

In order to hold the cover B in the proper position when open, the cover-support E is provided. In order to prevent the rod or bail F from striking the cover B, I place rubber buffers g on the cover, so that the rod will 85 strike them.

What I claim as new, and desire to secure by Letters Patent, is—

In a cabinet-file, the combination of a case provided with a cover, a series of pockets D, 90 to receive papers, a bent rod or bail F, under or behind which uplifted pockets can be passed, and springs G, to hold uplifted pockets against the inside of the cover, substantially as specified.

JOSEPH D. HUBBARD.
